UNITED STATES PATENT OFFICE.

JACOB W. BROWN, OF BOSTON, MASSACHUSETTS.

DESIGN FOR A GAME-BOARD OR SIMILAR ARTICLE.

SPECIFICATION forming part of Design No. 33,397, dated October 16, 1900.

Application filed May 3, 1900. Serial No. 15,422. Term of patent 3*i* years.

To all whom it may concern:

Be it known that I, JACOB W. BROWN, a citizen of the United States, residing at Boston, (Charlestown,) in the county of Suffolk and State of Massachusetts, have invented and produced a new and original Design for a Game-Board or Similar Article; and I do hereby declare the following to be a full, clear, and exact description of the same, reference being had to the accompanying drawing, forming a part thereof.

This invention relates to a design for a new and original game-board or similar article.

As shown in the drawing, the design comprises a flat plane rectangular surface A, provided with a large central circular field B, within which are arranged a number of small fields or spaces of similar size and design and which are numbered 1 2 3 4, &c., each of these spaces bearing a different number. The small spaces 1 2 3 4, &c., are not arranged regularly or in a particular order and are not equidistant, but are variously spaced from each other and in the manner shown. Besides the said small spaces 1 2 3 4, &c., two other small spaces C and D are provided, which are distinguished from the other small spaces and

from each other. Extending from each of the small spaces 1 2 3 4, &c., to one or more of the adjacent spaces are paths or narrow ways E of relatively different length and arranged as shown. Each of the spaces C and D is also connected by similar paths or ways, arranged as shown, to the adjacent small spaces.

The essential features of the design are a large field having therein the small spaces 1 2 3 4, &c., arranged at varying distances from each other and connected by the paths, and the two spaces C and D, distinguished from each other, connected to adjacent small spaces, substantially as shown.

Having thus described my invention, what I claim, and desire to secure by Letters Patent, is—

The design for a game-board or similar article, substantially as shown and described.

In testimony whereof I affix my signature in presence of two witnesses.

JACOB W. BROWN.
